WORKHOLDER FOR SHARPENING MACHINES

Leo Steiner, Budapest, Hungary

Application November 25, 1932, Serial No. 644,183
In Great Britain November 28, 1931

2 Claims. (Cl. 51—218)

- This invention relates to that type of work-holders for sharpening machines in which the work is rotatably mounted on a pivot so that a double-edge blade may present in succession both edges for sharpening without being removed from its position on the pivot. The chief object of the invention is to improve such work-holders so as to meet the requirements of that type of sharpening machines in which the work must have 5 unlimited freedom of movement in its own plane and the work-holder has to weigh upon the blade edge to be sharpened to obtain correct operation of the machine as, for example, in the machine described and claimed in my Patent No. 1,941,- 10 15, issued January 2, 1934. Other objects of the invention will appear from the following description of two constructional forms of the invention which are illustrated by way of example in the accompanying drawing in which—
- Fig. 1 is a side view of a constructional form of the invention as seen from the right of Fig. 2, Fig. 2 is an end view of the same constructional form, and Fig. 3 is a side view of a second constructional form.
- Referring first to Figs. 1 and 2 of the drawing, 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935

of the holder 4 between the guide rails 5 and 6, the purpose of such progress being described in my Patent No. 1,941,501 referred to above. Free displacement of the blade 10 in its own plane or in the vertical plane passing through its edge operated on is ensured by the fact that the blade can pivot about peg 12 on the holder and at the same time the whole of the holder together with the blade can pivot about the axis of roller 13.

When the free edge, i. e. the lower one in the drawing, of the blade 10 has been sharpened, the second edge of the blade may be presented for sharpening, without removal of the blade from its holder, by simply turning the blade through 180 degrees around peg 12, the inner faces of the wings being recessed at 15 so as to afford free passage to the blade in its intermediate position indicated by dot and dash lines in Fig. 1.

It will be understood that any further edge of the blade could be presented for sharpening, if desired.

In the constructional form of the work-holder shown in Fig. 3, the second point of support for the holder body 4 is provided for by clamping in two blades 10 and 10' in one holder, the pegs 12 and 12' being passed each through the middle hole of a blade. It will be understood that the double clamp 8' is so formed as to hold both blades 10 and 10' in one and the same vertical plane in which each blade may pivot or oscillate independently of the other.

It should be understood that the word "sharpening" as used in the description and claims is intended to include grinding, honing, burnishing, polishing and stropping.

What I claim is:—

1. A work-holder for use in blade sharpening machines, comprising a pivot adapted so to carry the blade as to enable it to be rotated and thereby present in succession several of its edges for sharpening without being removed from its position on the pivot, a second pivot located with its axis parallel to, and at a substantial distance from, the axis of said first pivot, and a supporting member rotatably mounted on said second pivot, each pivot forming a point of support for the work-holder, about which the work-holder can pivot in the plane to be occupied by the blade on said first pivot.

2. A work-holder as claimed in claim 2, where- 50 in the supporting member rotatable on the second pivot is another blade located in the plane to be occupied by the blade on the first pivot.

LEO STEINER.
